UNITED STATES PATENT OFFICE.

ISRAEL A. ROSHON, OF WORTHINGTON, MINNESOTA, ASSIGNOR OF ONE-HALF TO
PETER THOMPSON, OF WORTHINGTON, MINNESOTA.

ATTACHMENT FOR LINOTYPE-MACHINES.

1,081,989.

Specification of Letters Patent.

Patented Dec. 23, 1913.

Application filed August 26, 1912. Serial No. 717,168.

To all whom it may concern:

Be it known that I, ISRAEL A. ROSHON, a citizen of the United States, residing at Worthington, in the county of Nobles and State of Minnesota, have invented certain new and useful Improvements in Attachments for Linotype-Machines, of which the following is a specification.

This invention is an attachment to a linotype or slug casting machine, designed to maintain at all times a certain amount of metal in the metal pot by feeding thereto a single old slug after the removal of each charge of metal for the casting of a new 15 slug. By this means as sufficient metal is removed from the metal pot to cast each slug a like amount of metal in the form of an old slug is fed into the metal pot to make up for the amount that has been taken out. 20 To these ends the invention consists generally in the constructions and combinations hereinafter described and particularly pointed out in the claims.

In the accompanying drawings forming 25 part of this specification; Figure 1 is a side elevation, partially in section, of a linotype metal pot, and means for holding and moving the same with my newly invented slug feeding device attached thereto. Fig. 2 is 30 a rear elevation of the parts shown in Fig. 1, Fig. 3 is a detail showing the construction of the slide operating rod, Fig. 4 is a detail section of the slug holder, Fig. 5 is an elevation showing a portion of the frame of 35 the machine and means for securing the slug holder thereto, Fig. 6 is a transverse horizontal section of the slug holder, Fig. 7 is a side elevation thereof.

In the drawings, 2 represents the metal 40 pot of a linotype or similar machine, which is supported by suitable arms 4 upon a shaft 3.

5 is the slug ejector arm, which, in the machine, is given a rocking motion to operate 45 the ejector slide (not shown) which ejects from the mold each new slug after the same is cast.

I have not shown the means for forcing 50 the liquid metal from the metal pot into the mold, or the mold itself, or the means for ejecting the slugs therefrom as they are cast, as these parts are common to all linotype machines and in themselves form no part of my invention. It will be understood, however, that my invention is attached to the metal pot or other suitable

part of the linotype machine, and that its reciprocating slide hereinafter referred to is operated to correspond with the operation of the linotype machine in the casting of 60 each slug from metal removed from the metal pot.

In the particular embodiment of the invention illustrated in the drawings and described in the present specification, the movable ejector arm of the linotype machine, which causes the slugs to be successively ejected from the mold in which they are cast, is used as a means to which the feeding slide, hereinafter described, is connected 65 and by which it is operated. Any other movable part of the linotype machine which moves at, or immediately before, or after, the casting of a new slug from the metal discharged from the metal pot, may be employed 70 to move the feeding slide hereinafter referred to.

A light frame 5' preferably formed of metal supports the parts of the feeding mechanism. It is secured to the metal pot 80 by suitable arms 6. At its upper end it carries a horizontal table 7 secured to said frame by any suitable means, which may include suitable braces 8, and having near its forward end an opening or slot 9 above a 85 chute 10, which leads from the opening 9 in the table 7 to the metal pot, so as to be capable of discharging into said pot. The table 7 is preferably provided with guide-ways or grooves 11, and a distributing slide 12 is 90 arranged upon said table with its edges projecting into said grooves. Said slide is capable of being reciprocated upon said table, being guided by the engagement of its edges with said grooves. An arm 13 is connected to said slide and a connecting rod engages the arm 13, and has its opposite end connected preferably by a yoke 16 with the free end of the ejector arm 5. As here shown the connecting rod is made up of 100 three parts, the rod 17 having the yoke or hook 16 at one end which engages with a pin 5' on the ejector arm 5 and carries at its opposite end a nut 18; a rod 19 that is connected at one end directly to the arm 13 and has its opposite end screw threaded, and a turn buckle 20 into one end of which the rod 19 is screwed, while the rod 17 projects through the opposite end of said turn buckle and is provided with a spring 21, which surrounds said rod 17 and bears at one end upon the bottom wall of the socket of the turn 105 110

buckle, and at its other end upon the nut 18. This construction furnishes an extensible connecting rod, which may be lengthened or shortened at any time by turning the turn 5 buckle 20 and thereby moving the threaded end of the rod 19 out of or into the threaded opening in the end of said turn buckle.

The slide 12 is provided with an opening 12' (see Figs. 1 and 4) which is of sufficient 10 size to receive a single slug therein.

Rising from the frame of the machine are the posts or standards 25, 25, connected by the transverse bars 26 and 27, each of which is provided with a slot 28 and through which 15 slot extends a bolt 29. These bolts are provided with thumb nuts 30.

A slug holder 31 is placed vertically upon the machine frame and is secured in position by means of the bolts 29 which pass through 20 holes in the back plate of the slug holder 31 and through the holes 28 in the cross bars 26 and 27. By means of the bolts 29 and the nuts 30 the slug holder can be clamped to the cross bars 26 and 25 27, and the elongated form of the openings through which the bolts 29 pass permits of a certain amount of vertical adjustment of said slug holder in reference to the table 7 and slide 12. The other portion 30 of the slug holder is in the form of a rectangular open trough 32 in which the used slugs may be placed. This trough is preferably provided with a cross pin 33 near the end thereof that becomes the lowermost end 35 when the device is in position in the machine and which holds the slugs in the trough when said trough is placed in a vertical position. The slug holder section 32 may be secured in place on the back section 31 by 40 means of suitable hooks 34 (see Fig. 7). The end of the trough section 32 of the slug holder which is to be uppermost when the device is in position in the machine is provided with an end plate 35 having a hook 45 36 at its end and this hook is adapted to hook over the other end of the back section 31 when the slug holder is in place in the machine. (See Fig. 1.) When the slug holder is in position in the machine as shown 50 in Figs. 1 and 2, one end will be directly over the opening 12' in the slide or plate 12 and when said plate is in its retracted or receiving position the opening in the plate will register with the opening through the 55 slug holder and the lowermost slug on the carrier will drop into the slug opening in said plate and will rest upon the upper surface of the table 7. (See Figs. 1 and 4.)

Then, as the slide 12 is moved forward, after 60 each new slug is cast or is ejected from the machine, the lowermost slug in the stack which is within the opening in the slide will be moved forward until it comes over the opening 9 in the plate 7. It will then drop 65 into the chute 10 and passing down said

chute will fall into the metal pot, thereby supplying the said pot with the same amount of metal that has been removed for casting the new slug. I also prefer to provide on the outer wall of the slug holder a suitable 70 bell 35 with a hammer 36, having an end that projects through a slot in the wall of the slug holder, in position to be engaged by the slugs therein. (See Fig. 4.) When the slugs in the holder have become exhausted 75 the end will be released and will fly upward permitting the hammer to strike the bell to call the attention of the operator to the fact that a new supply of slugs is needed in the holder. 80

I have shown the device attached to the metal pot of a so-called junior linotype machine, but it will be understood that I am not limited to its application to any particular style or type of machine. It may 85 be used in connection with any slug casting machine.

In the operation of the ordinary linotype machine most operators, either through neglect or forgetfulness, fail to feed the metal 90 to the metal pot regularly as required, and, in consequence, cast a number of honeycombed or bad slugs before their error is discovered, or if too much metal is fed at a time they cast "cold" slugs with a bad 95 face, which are just as worthless, thus causing great annoyance and a loss of much valuable time. With my automatic metal feed this trouble is overcome or reduced to a minimum. When the metal is once at the 100 proper temperature and temper, with the burner adjusted properly, other than placing a galley in position when required, the machine needs very little or no attention as the automatic feed always replaces the metal 105 or slug one at a time as fast as the hot metal is taken from the pot, thus enabling the operator to give full attention to the keyboard with knowledge that his slugs are always being cast in good condition. With this attachment the same amount of metal always remains in the metal pot, and with the burner properly adjusted will always remain at practically the same temperature. 110

The device, it will be noted, is composed 115 of four separate detachable parts which can be easily adjusted to any linotype machine without in any way marring or defacing the same.

Changes in the details of construction may 120 be made without departing from my invention.

I claim as my invention:

1. The combination, with the metal pot of a linotype machine, of a rocking slug 125 ejector arm, and reciprocating means connected with said arm for automatically feeding slugs into said metal pot proportionately with the removal of the molten metal therefrom. 130

2. The combination, with the metal pot of a linotype machine, of a slug ejector arm and reciprocating means yieldingly connected with said arm for automatically feeding slugs into said metal pot proportionately with the removal of the molten metal therefrom.

3. The combination, with the metal pot of a linotype machine, of an ejecting device, a slug holder, a slide operating transversely of said holder, an arm connected to said slide, and an extensible rod connecting said arm with said ejecting device.

4. The combination, with the metal pot of a linotype machine, of a rocking ejecting device, a slug holder, a feed plate operating transversely of said slug holder, mechanism connecting said feed plate with said ejecting device for simultaneously operating to feed the slugs from said holder into said metal pot with the discharge of the molten metal from said pot.

5. The combination, with the metal pot of a linotype machine, and a rocking slug ejector arm therefor, of a slug holder, a reciprocating slug feeding slide arranged to

receive the slugs successively from said holder and to feed them into said metal pot, and means connecting said slide and said ejector arm, substantially as described.

30

6. The combination, with a metal pot, of a frame mounted thereon, a slug holder, a slug feeding means operating transversely with respect to said slug holder and adapted to engage the lower slug of the series and feed it from said holder into said pot, and a rocking ejector arm and means operatively connecting said arm with said slug feeding means.

35

7. The combination, with the metal pot of a linotype machine, of a slug holder, a slide operating to engage and feed the slugs from said holder to said pot, a rocking ejector device for the molten metal, and means yieldingly connecting said ejector device with said slide.

40

In witness whereof, I have hereunto set my hand this 21st day of August 1912.

ISRAEL A. ROSHON.
